UNITED STATES PATENT OFFICE

JOSEPH CICOUREL, OF NEW YORK, N. Y.

KEY COVER

Application filed April 26, 1930. Serial No. 447,888.

This invention relates to a cover for the handle part of a key, the general object of the invention being to provide means for identification of keys by making the covers of different colors or providing the covers with designs.

Another object of the invention is to make the cover of resilient material, such as rubber, so that it can be slipped over the handle part of the key.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view of a key, showing the cover in place.

Figure 2 is a sectional view through Figure 2.

As shown in these views, the cover 1 fits over the handle part 2 of the key 3 and the cover is shaped so as to snugly fit the handle part and as the cover is formed of rubber or the like, it can be stretched over the handle part as the same is pressed through the opening 4 at a part of the edge of the cover. The covers can be made of various colors so that a key with a cover thereon can be easily identified from a key having a cover of a different color, or the covers can be provided with different designs, projections or the like to distinguish them apart. The drawing shows the cover formed with a circular row of projections 5 for distinguishing it from a cover on another key. Of course, the cover is formed with the openings 6 which register with the opening in the handle part of the key.

It is thought from the foregoing description that the advantages and novel features of the invention will be readily apparent.

It is to be understood that changes may be made in the construction and in the combination and arrangement of the several parts,

provided that such changes fall within the scope of the appended claims.

What I claim is:

1. A key cover of the kind described, comprising a normally contracted flat hollow substantially circular-shaped body of resilient material to fit a correspondingly shaped head of a key and adapted to be removably fitted thereover, said body having a peripheral opening normally of a size considerably less than the wider extent of said key head whereby when the body is stretched the opening will permit the insertion of the key head therethrough for snug embracing of the body upon the head.

2. A key cover of the kind described, comprising a normally contracted flat hollow substantially circular-shaped body of resilient material to fit a correspondingly shaped head of a key and adapted to be removably fitted thereover, said body having a peripheral opening normally of a size considerably less than the wider extent of said key head whereby when the body is stretched the opening will permit the insertion of the key head therethrough for snug embracing of the body upon the head, and means on the body for distinguishing a key from another.

In testimony whereof I affix my signature.

JOSEPH CICOUREL.
